UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

BRAKE-SUPPORTING MEANS.

1,335,188.

Specification of Letters Patent. Patented Mar. 30, 1920.

Application filed August 26, 1918. Serial No. 251,355.

To all whom it may concern:

Be it known that I, ARMAND H. PEYCKE, a citizen of the United States, residing at Chicago, in the county of Cook and State 5 of Illinois, have invented certain new and useful Improvements in Brake-Supporting Means, of which the following is a specification.

This invention relates to brake supporting means.

The object of this invention is to support brake rigging in a novel and efficient manner such that there is freedom of movement of the movable parts, the arrangement occupying a relatively small space to increase clearances.

These and other objects are accomplished by means of the arrangement disclosed by the accompanying sheet of drawings, in 20 which—

Figure 1 is a fragmentary plan view of a railway car truck embodying my invention;

Fig. 2 is a fragmentary side elevation of 25 the same; and,

Fig. 3 is a detail sectional view showing the means for pivotally connecting the hanger and associated pull rod.

The various novel features of the invention will be apparent from the following 30 description and drawings and will be particularly pointed out in the appended claims.

Referring to the figures of the drawings, 35 it will be noted that I have shown a railway car truck including a side frame 10, the opposite ends of which (only one end being shown) are extended beyond the associated truck wheels 11. The upper surface 40 of the truck side frame 10 slopes downwardly toward the ends. Secured to the end of the side frame is a bracket 12 which extends upwardly and laterally with respect to the side frame, said bracket having

45 a slot 13 therein through which a brake lever 14 extends, the upper end of the brake lever being operatively connected to a pull rod 15, a brake beam 16 being connected to the lower end of the brake lever. The upper end of a hanger 17 extends through the 50 slot 13 and is pivotally connected between upwardly extending ears 18 formed integrally with the bracket 12, the lower end

of the hanger 17 being connected between the jaws 19 of an intermediate pull rod 20, 55 these same jaws being arranged on opposite sides of the brake lever 14 and pivotally connected thereto by a pin 21. Preferably the lower end of the hanger 17 is pivotally connected to a bushing 22 which 60 holds the jaws 19 a predetermined distance apart when the rivet 23 passing through the bushing and the jaws is secured in place, thereby providing a pivotal connection which permits freedom of movement. The 65 hanger 24 has its upper end pivotally connected to a bracket 25 preferably formed integrally with the truck side frame and extending laterally with respect thereto, the lower end of the link 24 being pivotally 70 connected between the oppositely arranged jaws of the intermediate pull rod 20, there also being a brake lever 28 connected between said jaws. This brake lever 28 has connected at its upper end another pull rod 75 26, and at its lower end is connected to a brake beam 27. The bracket 25 is wholly within the vertical contour of the truck side frame 10, while in order to maintain the pull rod 20 in a horizontal position, the 80 ear members 18 of bracket 12 are extended upwardly to a point beyond the vertical confines of the truck side frame. The pull rods 20 are located intermediate the truck side frame and the associated truck wheels, 85 and although there is a relatively small space therebetween, the hanger brackets are so arranged as to permit adequate clearance.

By means of this arrangement a brake supporting means is provided which is 90 adapted to meet the service requirements, the arrangement being particularly adapted for freight equipment.

It is my intention to cover all modifications of the invention falling within the 95 spirit and scope of the following claims.

I claim:

1. In a railway car truck, the combination of a truck side frame, the upper surface of which slopes downwardly in a longitudinal direction, said truck side frame having a bracket intermediate the ends thereof and being within the vertical confines of the frame and having another bracket having a portion extending above the vertical 105 confines of said frame, brake rigging hang-

ers connected to said brackets, and a pull rod connected to said hangers and occupying a horizontal position.

2. In a railway car truck, the combination of a truck side frame having an end portion extending beyond the truck wheels, a bracket secured to the end portion, a

brake rigging hanger connected to said bracket, another hanger operatively connected to the frame, and a pull rod directly 10 pivotally connected to both of said hangers.

Signed at Chicago, Illinois, this 19th day of August, 1918.

ARMAND H. PEYCKE.
